UNITED STATES PATENT OFFICE.

HARRY J. SHEPARD, OF NEW YORK, N. Y.

DESIGN FOR A DOLL.

54,464.

Specification for Design.

Patented Feb. 10, 1920.

Application filed July 14, 1919. Serial No. 310,866. Term of patent 14 years.

To all whom it may concern:

Be it known that I, HARRY J. SHEPARD, a citizen of the United States, residing at the city, county, and State of New York, have invented a new, original, and ornamental Design for Dolls, of which the following is a specification, reference being had to the drawing forming part thereof.

The figure is a front view of a doll, showing my new design.

I claim:

The ornamental design for a doll, substantially as shown.

HARRY J. SHEPARD.
